UNITED STATES PATENT OFFICE.

CHARLES L. TURNER, OF JERSEY CITY, NEW JERSEY.

ELECTRIC SWITCH.

Application filed August 24, 1923. Serial No. 659,060.

To all whom it may concern:

Be it known that I, CHARLES L. TURNER, a citizen of the United States, residing at Jersey City, county of Hudson, and State 5 of New Jersey, have invented certain new and useful Improvements in Electric Switches, of which the following is a specification, reference being had to the accompanying drawings.

This invention relates to switches and it has more particular reference to electric switches of the type commonly employed on automotive vehicles for controlling the supply of current to the ignition whereby the 10 combustible mixture is ignited or exploded. Switches of the kind referred to usually comprise an associated key-operated mechanism adapted to lock the same in the "off" position when the vehicle is not in operation, whereby the ignition circuit is broken. Devices of said type while effective in most respects have inherent disadvantages, primarily of which is consequent upon forgetfulness to properly adjust the switch to the 15 "off" position and remove the key when the vehicle is left unattended, or parked. Furthermore, it frequently happens that through neglect and various other reasons a switch of the type referred to is not properly locked when cut-out whereby an unauthorized person may, with comparatively little trouble, move said switch to the "on" position and illicitly operate the vehicle. Keeping in view the aforesaid 20 disadvantages I provide a switch which effectively overcomes said disadvantages in a simple, thorough and reliable manner.

Another object of my invention is to provide a switch of the type specified, characterized by the fact that the movement of said switch to the "off" position automatically locks the same against unauthorized operation or use.

Other objects and attendant advantages 45 will be obvious from the following description while the scope of my invention will be readily apparent from the appended claims.

Briefly outlined my invention consists of 50 a permutation switch, the movement of

which to the "off" position simultaneously breaks the permutative combination, so that anyone other than the properly authorized person knowing said combination cannot reset the switch. 55

In the drawings, Fig. I is a longitudinal section through an ignition switch embodying my invention and adapted for installation on the dash board or instrument panel of an automotive vehicle. 60

Fig. II is a front elevation of the same.

Fig. III is a sectional elevation taken approximately on the lines III—III in the preceding Figure, and as viewed in the direction of the arrows. 65

Fig. IV. is an enlarged detail view of one of the permutative switch members.

Fig. V is a sectional view thereof.

Fig. VI is a section taken substantially on the line VI—VI in the preceding Figure; 70 and

Fig. VII is an enlarged sectional detail of a contact hereafter more particularly referred to.

In carrying out my invention in accordance with the embodiment illustrated by the aforesaid drawings I make a base or support 7 of a non-conductive material such as bakelite or the like, and said base 7 is fashioned or formed at spaced intervals with clefts or recesses 8 disposed in parallel planes. These clefts or parallel recesses 8 have an aligned series of contact devices 9 slightly projecting thereinto for a purpose hereafter fully explained, each of 75 said contact devices 9 embracing a tubular sleeve 10 housing a contractile spring 11 and opposed contact instrumentalities or balls 12 that are protected against accidental loss by an inward retaining lip or flaring 13 80 at each end of said sleeve 10, as best seen in Fig. VII. The contractile springs 11 tend to urge the balls 12 apart and slightly beyond the opposite ends of the sleeve 10. Said contact devices 9 are made 85 a friction fit into corresponding aligned bores 14 in the base 7, and it will be remarked that they are of an over-all dimension to snugly register at their ends with the clefts or recesses 8, with the balls 12 pro- 90

projected thereinto. Furthermore it will be observed that the outer contact devices 9' are preferably only provided with one ball 12', the same projecting into the contiguous end 5 cleft or recess 8. Likewise the outer ends of the contact devices 9' are approximately constructed to provide binding posts or terminals 15 to which the wires 16, 17 in circuit with a battery 18, distributor and spark 10 plugs—not shown—or other instrumentalities and devices included in said circuit are attached by lock nuts 19. With the foregoing assemblage of contacts 9, 9' it will be readily seen that each cleft or recess 8 15 is provided with opposed and axially registering balls 12 or the like projecting thereinto.

Traversing the aforesaid clefts or recesses 8 is a rod or shaft 20 that serves as the axis for a plurality of independently rotatable switch or permutative members 21 substantially housed in the clefts or recesses 8, one of said switch or permutative members 21 being located in each recess 8 and adapted for rotation, as hereafter more fully explained. These switch or permutative members 21 may be made entirely of non-conductive material, but it will be seen from the drawings which exemplify a practical and preferred form of construction, said switch or permutative members 21, each comprising a main or body portion 22 of insulate material having a metallic surrounding ring or toothed peripheral portion 23. This ring or toothed portion 23 may be secured to the main or body portion 22 in any convenient manner that will prevent relative movement; or, as shown, the body portion 22 may be provided with a peripheral groove 24 into which fits a correspondingly shaped rib 25 on the inner face of the toothed portion 23, whereby lateral movement is effectively prevented. On the other hand, relative rotation of the parts is prevented by means of radial projections 26 on the body portion 22 embedded in corresponding recesses 27 in the peripheral portion 23, it being obvious such a combination of parts will be accomplished by moulding or the like. On an examination of Figures IV, V and VI, it will be noted that each of the aforesaid peripheral portions 23 is formed with a plurality of evenly configured undulations or teeth 28, and a mutilated tooth or stop 29, for a purpose later on explained. Adapted for operative engagement with the teeth 28 of each switch or permutative member 21 is an anti-friction plunger or ball 30 influenced by a spiral spring 31, housed within a bore 32, in the base 7 that is closed at its outer end by a removable plug 33, and all of said plugs 33 are conveniently closed in and protected by means of a covering strip or member 34 secured to the said base 7 by countersunk

screws 35. The balls 30 are freely traversable by the teeth 28, 29, and snap into the undulations between same when the permutation members 21 are rotated in one direction, but the mutilated tooth 29 will arrest rotation of said members 21, when reversely rotated. 70

As best seen from Figures III and IV the switch or permutation members 21 are freely rotatable in a clockwise direction but their rotation is limited and arrested when turned in a contra-clockwise manner by the mutilated tooth or stop 29, vide the showing in Figure IV, but it will be quite obvious the direction of said tooth or stop 29 may be reversed with a similar reversal of permutative rotation for the members 21. 75 80

It will of course be well understood that the balls 30 are located in registry with the clefts or recesses 8 in the base 7 and in operative engagement with the switch or permutative members 21, and each of said members is provided with an inserted metal contact 36 extended transversely through the insulate body portion 22 so that its opposite ends are exposed at the plane surfaces thereof. Furthermore it will be seen that the metal contact 36 is located eccentric relative to the axis of the switch or permutative member 21, so that by rotation of said member 21 it may be brought into registry and engagement between a pair of opposed balls 12-12 or 12-12' and thereby close an electric circuit through the device terminals 15, wires 16, 17 and the battery 18. The contacts 36, it will be noted from Figure IV, are located at predetermined and different points in each switch or permutative member 21 with respect to the mutilated tooth or stop 29; or, said contacts 36 are located at the same radial centers, but relatively different arcuate positions with respect to said tooth or stop 29. It will thus be apparent that the location of the contacts 36 determines the number of progressive steps through which each permutative member 21 must be rotated to carry its contact 36 into registry with its contiguous balls 12-12 or 12-12'. A large number of permutations are thus rendered possible so that each device can be set to an individual combination to be known only to the owner, or other properly authorized person, whereby the closure of a circuit therethrough by an unauthorized person becomes a remote possibility. By way of example let it be assumed that the combination of the particular device shown is thirteen-fifty-seven, as indicated on Figure IV, the contact 36 of the outer switch member 21 at the left-hand side in Figure I will require one tooth or one step actuation to bring said contact 36 into registration with its co-operating plungers or balls 12-12, it being understood that the steps 130

are counted from the point at which the mutilated tooth or stop 29 engages its co-operating ball 30. Similarly the successive permutative members 21, due to the particular location of the respective contacts 36 therein, will respectively require a three, five, and seven step actuation to bring said contacts 36 into axial alignment, with their associated plungers or balls 12-12'.
 10 In use, and assuming the device is in the "off" or inoperative position and that it is desired to close a circuit therethrough, the switch or permutative members 21 are all rotated in one direction until further movement is arrested by the engagement of the respective mutilated teeth 29 with their co-operating balls 30, to establish the datum or starting point. The first or left-hand switch member 21 is now moved in the opposite or forward direction the distance of one tooth 28, or one step away from its co-operating ball 30 as audibly indicated by the snapping of said ball 30 into the undulation intervening the first and second teeth 25 28 away from the mutilated tooth 29; and said operation results in the registering engagement of the contact 36 with its co-operative balls 12'-12'. The next switch member 21 advancing towards the right hand 30 is now turned a distance corresponding to three steps as indicated by the successive snapping of its co-operating ball 30 into three successive recesses intervening its teeth 28, and as a result the contact 36 there- 35 in will be moved into aligned registration with the contiguous contact balls 12, 12. Similarly the successive switch or permutative members 21 advancing to the right will be respectively moved five and seven steps 40 as audibly indicated by the successive snap- 45 pings of their co-operative plungers or balls 30. As a result of the permutative movements first described it will be clear that the particular combination predetermined will be completed and all of the contacts 36 and 50 cooperating balls 12'-12-12' brought into registering alignment—as shown in Figure II—whereby a circuit will be closed through the battery 18 to the ignition and other devices to be energized thereby. To break the 55 circuit established by the means, and in the manner just described, it is only necessary to rotate or move one of the switch members 21 through one or more steps which results in the moving of its contact 36 out of registering alignment with the others. In such a case it becomes only necessary to remember how many steps and which selected switch or 60 permutative member 21 was operated, and to reversely actuate same to again promptly complete the circuit. However, to more effectively ensure safety and to reduce all possibility of an unauthorized person establishing the proper combination, it is advisable, to move all of the respective switch 65

members 21 in diverse relation to break the circuit in a multiplicity of places, so that it will be necessary to move all said members 21 to their datum position as before described. 70

To further reduce the possibility of detecting the particular combination of my novel switch, and also to minimize the possibility of short circuiting, said switch may conveniently be mounted by screws 37 on a 75 plate 38 having elongated slots 39 therein and said plate appropriately secured by screws or the like 40 on the dash or instrument board 41, of an automotive vehicle. Obviously such a mounting of my novel 80 switch will involve its recession relative to the front or face of the dash or instrument board 41 and to better protect the device from dust and dirt it is preferably closed in by means of a casing 42 held in place by wood screws or the like 43, as will be readily seen from an examination of Figures II and III more particularly. Further, by locating the contact instrumentalities or balls 12, 12' and springs 11 in the tubular sleeves 10, the latter assist in the conduction of electric current and effect a reliable connection when the switch is closed. 85 90

While my switch is particularly adapted for use on automotive vehicles as a safety 95 locking device; it will be obvious the same is equally usable wherever a safety locking circuit controller is desirable, therefore the embodiment disclosed is to be construed as by way of example only. 100

Various changes in the specific form of my invention illustrated and described may be effected without departing from its fundamentals, for example the contact instrumentalities or balls 12, 12' and springs 11 may be located directly in the bores 14 thereby eliminating the tubular sleeves 10, and the right is accordingly reserved to make all such reasonable modifications as fairly lie within the scope of the appended 110 claims. 105

By my invention I provide an exceptionally effective permutation switch and locking device, wherein the mere operation of one or more of the switch members 21 serves not only to break the electrical circuit and temporarily destroy electrical connection, but by breaking the combination coincidentally without any independent operative step, effectively locks the device with which the switch is associated; and such features is deemed of prime importance as the switch cannot be re-closed and the electrical connection re-established only by someone acquainted with its particular combination, 115 due to the multiplicity of permutations possible with only four members 21 as hereinbefore described. Other, important advantages inhering are so apparent it is deemed unnecessary to enumerate the same 120 125 130

herein beyond mention of the fact no removable key is needed with its attendant possibility of loss or misplacement.

Having thus described my invention, I claim:

1. An electric switch comprising a base provided with a series of open recesses, a corresponding series of permutative switch members journalled therein for step-by-step 10 rotation, axially aligned contacts inset in said base adapted for co-operative circuit-closing engagement with the switch members when permutatively moved, and an arresting datum for establishing a predetermined 15 mined permutation.

2. A permutation electric switch comprising a base formed with a plurality of open recesses, a corresponding plurality of movable switch members journalled therein for 20 step-by-step rotation, aligned end-to-end contacts in said base between the recesses and adapted for circuit-closing co-operation with the movable switch members when permutatively turned, and an arresting datum 25 for establishing a predetermined permutation.

3. An electric switch comprising a base formed with a plurality of open recesses, a corresponding plurality of switch members 30 journalled therein for step-by-step rotation, intervening axially aligned contacts in said base adapted for circuit-closing engagement with the movable members when permutatively rotated, and an arresting datum for 35 establishing the permutation.

4. An electric switch comprising a non-conductive base having a plurality of spaced open recesses, a corresponding number of rotatable switch members journalled in said 40 recesses, means limiting the rotation of said members in one direction to establish a datum, aligned end-to-end spring-influenced contacts intervening the aforesaid recesses adapted by engagement with conductive-insets in the rotatable members when permutatively moved to close an electric circuit, and means controlling a step-by-step movement of the aforesaid switch members.

5. An electric switch comprising a base having a plurality of spaced recesses, a corresponding number of rotatable members journalled in said recesses, means limiting the rotation of said members in one direction to establish a datum, aligned spring-influenced contacts intervening the aforesaid recesses and adapted for co-operation with the rotatable members when permutatively moved to close an electric circuit, and spring influenced plungers for effecting a 55 step-by-step movement of the aforesaid rotatable members.

6. A switch comprising a base, an interrupted line of contacts therein, a plurality of switch members movably mounted on said 60 base, means for arresting the movement of

said members in successive steps and contacts carried by said switch members and adjustable thereby to complete said line of contacts, said switch member contacts being located thereon in predetermined relation to 70 said arresting means to establish predetermined combinations.

7. A switch comprising a base provided with a plurality of open recesses, an interrupted line of contacts in said base in operative relation to said recesses, switch members rotatably mounted in said recesses, means for arresting the rotation of said switch members in successive steps, means for stopping the rotation of said switch members at given points, and contacts carried by said switch members and adjustable thereby to complete said line of contacts, said switch member contacts being located thereon in predetermined relation to 75 said stop means to establish predetermined combinations.

8. A switch comprising a base provided with a plurality of open recesses, resilient contact members in said base projecting into 90 said recesses from opposite directions to form an interrupted line of contacts, a plurality of switch members rotatably mounted in said recesses, means for arresting the rotation of said switch members in successive 95 steps, stops on said switch members for stopping the rotation thereof at given points, and contacts carried by said switch members and adjustable thereby into registry and engagement with said contact members to complete 100 said line of contacts, the contacts being located on said switch members at predetermined points to establish predetermined combinations.

9. A switch comprising a base provided 105 with a plurality of open recesses, metallic sleeves in said base extending between and terminating at said recesses, contact-plungers located in said sleeves and projecting beyond the same into said recesses, coil 110 springs in said sleeves whereby said contact-plungers are yieldingly maintained in position, rotatable switch members mounted in said recesses and provided with recessed peripheries, spring pressed stop-plungers in 115 said base for engaging said recessed peripheries to arrest the rotative movements of said switch members in successive steps, stops on said switch members for stopping said rotative movements of the switch members at given points, and contacts carried by 120 said switch members and adjustable thereby into registry and engagement with said contact-plungers to complete an electrical circuit through said switch, the contacts being 125 located in said switch members at predetermined points to establish predetermined combinations.

10. A switch comprising a base provided 130 with a plurality of open recesses, metallic

sleeves in said base extending between and terminating at said recesses, contact-plungers located in said sleeves and projecting beyond the same into said recesses, coil springs in said sleeves whereby said contact-plungers are yieldingly maintained in position, rotatable switch members mounted in said recesses, means for arresting the rotative movements of said switch members in successive 10 steps, and contacts carried by said switch members and adjustable thereby into regis-

try and engagement with said contact-plungers to complete an electrical circuit through said switch, the contacts being located on said switch members at predetermined points to establish predetermined combinations. 15

In testimony whereof, I have hereunto signed my name at New York, N. Y., this twenty-third day of July, 1923.

CHARLES L. TURNER.
